ATTORNEY.

UNITED STATES PATENT OFFICE

JAMES G. GRACEY, OF ST. LOUIS, MISSOURI, ASSIGNOR TO ECONOMIC PROPELLER COMPANY, OF ST. LOUIS, MISSOURI, A CORPORATION OF DELAWARE.

PROPELLER AND CURRENT-MOTOR.

1,296,792.

Specification of Letters Patent. Patented Mar. 11, 1919.

Application filed February 7, 1916, Serial No. 76,691. Renewed August 10, 1918. Serial No. 249,356.

To all whom it may concern:

Be it known that I, JAMES G. GRACEY, a citizen of the United States, residing at St. Louis, State of Missouri, have invented certain new and useful Improvements in Propellers and Current-Motors, of which the following is a full, clear, and exact description, reference being had to the accompanying drawings, forming a part hereof.

10 My invention has relation to improvements in propellers and current motors; and it consists in the novel features of construction more fully set forth in the specification and pointed out in the claims.

15 The present invention is directed to a class of propellers (and current motors) on the order shown and described in my U. S. Patent No. 930,956 dated August 10, 1909, the present being an improvement on the 20 construction shown in said patent. The objects here sought are identical with those enumerated in the specification of the patent aforesaid, the improved structure however possessing material advantages over 25 the old, especially in the matter of reducing friction. In the present embodiment of my invention the propeller blades do not traverse the radial ways or grooves formed in the face of the raceway disk as in the old 30 construction, but terminate wholly outside said disk, the shafts of the blades being mounted in disks or driving members through which the shafts loosely pass. The 35 advantages of the invention will be fully apparent from the following detailed description in connection with the accompanying drawings in which—

Figure 1 represents an elevation of my propeller shown conventionally applied to 40 the stern of a boat; Fig. 2 is a top plan of the apparatus with the boat omitted; Fig. 3 is a rear elevation; and Fig. 4 is a vertical transverse section on the line 4—4 of Fig. 1.

45 Referring to the drawings, B represents the rear end of a boat or vessel to which the frame F is secured in any suitable mechanical manner. Mounted in the frame F is one end of a drive-shaft 1 to which rotation is imparted by a motor or engine on the boat 50 (the motor not being shown), the shaft terminating at its outer end in a bevel gear 2 which meshes with a similar gear 3 on a countershaft 4 having its bearings in the frame F. One end of the shaft 4 carries a gear 55 wheel 5 which meshes with a gear 6 at the

adjacent end of a parallel hollow shaft 7, the opposite end of the hollow shaft terminating in the disk or equivalent rotatable member 8. The ends of the shaft 7 are received by the hollow hubs h, h', of the gear 6 and disk 8 respectively (Fig. 4), said hollow shaft being traversed from end to end by a stationary axle or supporting rod 9 having at one end an enlarged head 10 loosely fitting one end of the hollow shaft, 65 the opposite end of the axle terminating in an enlarged elongated head 11 which fits loosely in the shaft 7 and passes through the hub h, the projecting end of said head 11 being set-screwed to a bearing a formed in 70 the adjacent member of the frame F. Formed on, or secured to, the frame F is a standard 12 terminating in a bearing 13 in which is rotatably mounted the trunnion or spindle 14 of a race-way disk or member 15. 75 The race-ways or grooves m on the inner face of said disk 15 are on the order shown in my patent aforesaid, in the present case three such ways being shown intersecting at the axis of the disk. These ways are traversed by blocks or slides 16 which are rigidly secured to the shafts 17 supporting the 80 blades 18, the latter being disposed symmetrically about their shafts. There are three blades and three blade-shafts corresponding 85 to the number of race-ways, the shafts 17 being parallel and passing loosely through the members 6 and 8, at points which in the normal operation of said members, will successively come in alinement with the axis of 90 the race-way member 15 (Fig. 1), the blade-shafts 17 being positioned at the centers of 95 their respective race blocks 16. The members 6 and 8 of course are mounted eccentrically to the disk 15.

The operation will now be clear from the foregoing description and is substantially as follows: Rotation (in proper direction) being imparted to the shaft 1, it follows, 100 from the connections described, that rotation will be communicated to the gear wheel 6. The gear 6 will in turn carry around the shafts 17 and necessarily will cause rotation to be imparted to the disk 8. This in turn will cause a circular sweep to be imparted to the blocks 16, the latter reciprocating through their respective race-ways m (without fouling one another) thereby 105 imparting rotation to the disk 15, the same as in my patent aforesaid. In a hand pro- 110

steller the member 15 which is here shown as the driven member, may be used as the driving member, it being immaterial to the invention at which end the power is applied.

Of course with the traverse of the blocks 16 back and forth along the race-ways *m* of the member 15 during the rotation of the latter, rotation will necessarily be imparted 10 to the blade-shafts 17 and hence to the blades 18. In their rotation about their own individual axes, and in their revolution about the common axis of the members 6 and 8, the blades operate through the water 15 in the same manner described therefor in my patent aforesaid, and a repetition of this feature is not necessary in the present description.

In the present embodiment of my invention, the blades are clear of the disks 6 and 8, their shafts 17 being freely rotatable in the disks; the hollow shaft or sleeve 7 connecting and supporting the disks 6, 8, revolves freely on the axle or inner rod 9, the 25 rubbing surfaces being kept well lubricated, as well as the rubbing surfaces between all other relatively movable parts. The rod 9 insures stiffness for the structure making it possible to utilize the propeller as a current 30 motor by a proper degree of submergence of the apparatus in a running stream. This convertibility however from a propeller to a current motor and from a current motor to a propeller is likewise inherent in the 35 structure of my patent aforesaid, the two structures having this feature in common. I may of course depart in a measure from the details here shown without in any wise affecting the nature or spirit of my invention. 40 Features shown but not alluded to are either well known in the art, or are already fully described in my patent aforesaid. In the present illustration and assuming the apparatus operates as a propeller, 45 the disks 6 and 8 may be considered as the driving members.

Having described my invention what I claim is:

1. In combination with a rotatable member provided with a series of race-ways disposed diametrically and intersecting at the axis of said member, a pair of rotatable driving members spaced apart and mounted to rotate about a common axis eccentric to the axis of the race-way member, blade-shafts supported loosely by, and between the driving members, blocks secured to one of the terminals of the blade-shafts and free

to traverse the race-ways, and blades on the shafts between the driving members, substantially as set forth. 60

2. In combination with a rotatable member provided with a series of radial race-ways, a pair of rotatable driving members spaced apart and mounted to rotate about a common axis eccentric to the axis of the race-way member, a hollow shaft connecting the members aforesaid, a stationary rod serving as a bearing for and traversing the hollow shaft, one end of the rod projecting 65 outside the hollow shaft and beyond one of the rotatable driving members, means for rigidly supporting said projecting end of the rod, parallel shafts mounted loosely in and between the driving members, one end 70 of each shaft projecting beyond the driving member which is adjacent the race-way member, blocks rigidly secured to said shafts and free to traverse the race-ways, and blades mounted centrally and rigidly to the 75 shafts between the driving members and clearing said members.

3. In a current motor or propeller, a pair of rotating members disposed about a common axis and spaced apart, shafts disposed 80 parallel to said axis and operating loosely in and between the members, blades secured to rotate with the shafts, a member disposed adjacent to the first members and rotatable about an independent axis eccentric to the 85 axis of the first mentioned members, and slides disposed about the axis of the shafts coöperating with the last mentioned member for causing a simultaneous rotation of the 90 blades about their individual axes, and a 95 revolution of the blades and their shafts about the common axis of the first mentioned rotatable members.

4. In combination with a rotatable member provided with a series of race-ways disposed diametrically and intersecting at the axis of said member, a pair of rotatable driving members spaced apart and mounted to rotate about a common axis eccentric to the axis of the race-way member, blade-shafts supported loosely by, and between the driving members, slides secured at the terminals of the blade-shafts and free to traverse the race-ways, and blades on the 100 shafts between the driving members. 105

In testimony whereof, I affix my signature, in presence of two witnesses.

JAMES G. GRACEY.
